UNITED STATES PATENT OFFICE.

ALFRED HEALD, OF PHILADELPHIA, PA., ASSIGNOR TO HUGH McCALLUM,
ORLANDO CREASE, AND ANDREW J. SLOAN, OF SAME PLACE.

DESIGN FOR CARPET-PATTERN.

Specification forming part of Design No. **11,300**, dated July 22, 1879; application filed June 16, 1879.
[Term of patent 3½ years.]

To all whom it may concern:

Be it known that I, ALFRED HEALD, of Philadelphia, Pennsylvania, have produced or invented a new and original Design for a Carpet-Pattern, of which the following is a specification.

My design for a carpet-pattern is shown in the accompanying photographic illustration; and consists of a groundwork of a reticulated or net-work character, on which are stems, leaves, and clusters of blossoms, the character and arrangement of the latter being too fully shown in the illustration to need any detailed description.

Irrespective of the colors employed, I claim—

1. The design for a carpet-pattern, consist-

ing of stems, leaves, and clusters of blossoms, all substantially as described, and as shown in and by the accompanying illustration.

2. The design for a carpet-pattern, consisting of stems, leaves, and clusters of blossoms arranged on a groundwork of a reticulated or net-work character, all substantially as described, and as shown in and by the accompanying illustration.

In testimony whereof I have signed my name to this specification in the presence of two subscribing witnesses.

ALFRED HEALD.
